UNITED STATES PATENT OFFICE.

ALBERT SUTTON, OF ARBOR HILL, IOWA.

IMPROVEMENT IN CORN AND SEED PLANTERS AND ROLLERS.

Specification forming part of Letters Patent No. **222,546**, dated December 9, 1879; application filed July 12, 1879.

To all whom it may concern:

Be it known that I, ALBERT SUTTON, of Arbor Hill, in the county of Adair and State of Iowa, have invented a new and valuable Improvement in Corn and Seed Planters and Rollers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a top view of my invention. Fig. 2 is a detail side view thereof. Fig. 3 is a longitudinal vertical section of the same; and Figs. 4, 5, 6, and 7 are details.

This invention has relation to improvements in roller corn-planters; and the nature of the invention consists in certain novel combinations of devices used, whereby useful results are obtained, as will be hereinafter more fully set forth.

In the annexed drawings, the letter A designates a strong rectangular frame composed of a combination of wood and iron, or of iron wholly, and braced transversely by the beams *a a'*.

B B' designate rollers of suitable construction, arranged at each end of the frame, and journaled, respectively, in the end bars, *b*, thereof at one end, and at the other in the beams *a a'*. Between these rollers is a third roller, *B²*, having its bearings in the rear extensions, *c*, of the tongue-hounds *C*. These extensions pass under the front beam, *d*, of frame A, and their rear ends are journaled or pivoted to its rear beam, *d'*, as shown in Fig. 1.

D' represents the seat-support, rigidly secured to the tongue or tongue-hounds, and extending to the rear in a position overhanging the center roller, *B²*. This support is made unusually rigid and strong at its vertical portion *e*, and is provided upon its edge with a series of serrations, forming a ratchet, *e'*.

Extending up from the front beam, *d*, of the frame A is an upright bar, *d²*, to which is adjustably pivoted the end of a vertically-vibrating lever, *d³*, having its fulcrum at *e²* on the seat-support.

The end bars and braces in which the rollers *B B'* are journaled vibrate vertically on the

rear beam, *d'*, of the frame, and the weight of the center roller, *B²*, keeps that end of the frame down. Consequently, if the lever *d³* be thrust down over the ratchet *e'*, the front end of the frame will rise, and the end rollers, *B B'*, be cleared of the ground. The apparatus may then be turned round with great facility.

In rear of the rollers, and journaled in the end bars of the frame, is a metallic or metal-shod scraper, *F*, that extends from end to end of the frame A, and straddles the braces *a a'* and extensions *c* of the hounds, notches being cut in its edge for the purpose. This scraper is thrust into contact with the rollers *B B' B²* by means of a lever, *E*, when it is necessary to clear away any accumulation of earth thereon.

In front of the roller and secured to the frame is a seed-hopper, *J*, extending from end to end of said frame, and having a number of partitions, *f*, designed to be used only when planting corn, and to be removed when drilling small grain. Extending through this hopper lengthwise is the dropper-slide *G*, having any practical number of seed-holes, the dimensions of which may be regulated at pleasure according to the size of the grain, or closed altogether. This slide has an upturned end, *f'*, outside of the hopper, to which the retracting-spring *S* is secured at one end, its other end being attached to the end of hopper.

Each of the seed-holes of the slide acts in connection with a spout, *g*, at the rear of a standard, *g'*, carrying on its lower end a furrow-opener, *g²*, and a furrow-closer, *g³*, and the said standards depend from a strong metallic rod, *h*, extending from end to end of the frame.

The upper edge of the opener engages in a fork at the end of a rigid arm, *h'*, extending downward from the front beam of the frame, and the standard and its attachments are held against swinging backward by a pin, *i*, extending through coverer in front of the stop-arm *h'*. Should the opener, however, meet an unyielding obstacle, the pin *i* will break and allow the standard to swing back and clear the same instead of being carried away.

H indicates a cam-wheel rigidly keyed or secured upon the end of the shaft or spindle of roller *B'*, and provided on one face with two cam-surfaces, *i'*, and on the other with a num-

ber of such surfaces, i^2 , proportionate to the distance apart of the plantings desired; and H' indicates a strong metallic rod, loosely connected at one end to the dropper-slide aforesaid, and similarly connected to the spindle aforesaid outside of the cam-wheel, but in contact therewith, this contact being maintained by the spring S .

The rotation of the roller actuates the cam and lever and operates the slide, undue friction being avoided by an anti-friction roller, j , on the rod. In practice, the face of the wheel H , having the two cam-faces i' , is designed to drive the slide so as to plant at every three and one-half feet apart, and the other face at every eight inches apart; but it is clear that the intervals may be varied by using other cams.

What I claim as new, and desire to secure by Letters Patent, is—

1. In a seed-planter, the combination, with the frame A , having rollers B B' journaled in its ends, of the tongue-hounds C , having rear

extensions, c , extending under the frame and vibrating on its rear bar, the center roller, B^2 , journaled in extensions c , the ratcheted seat-support D' , upright d^2 , erected on the frame, and lever d^3 , pivoted to said upright and fulcrumed on the seat-support, substantially as specified.

2. The combination, with the rollers B B' , journaled one at each end of a frame, and an intermediate roller, B^2 , journaled in a rear extension of the tongue-hounds pivoted to the rear part of said frame, of a mechanism mounted on the hounds and tilting the front end of the frame, whereby the end rollers are lifted clear of the ground, substantially as specified.

In testimony that I claim the above I have hereunto subscribed my name in the presence of two witnesses.

ALBERT SUTTON.
